THREAD CUTTER FOR SEWING MACHINES

Hans Hacklander, Linden, N. J., assignor to The Singer Manufacturing Company, Elizabeth, N. J., a corporation of New Jersey

Application November 13, 1939, Serial No. 303,945

9 Claims. (Cl. 112—252)

This invention relates to improvements in sewing machines, and more particularly to improvements in sewing machine thread-cutters adapted to sever the thread-chains connecting stitched articles, such as filled bags and the like.

The primary object of the present invention is the provision of an improved thread-cutter of the type in question which is effective to cut the thread-chain between stitched articles without stopping the sewing machine.

Another object of the invention is to provide a thread-cutter which is simple in construction, durable, and requiring sharpening at protracted periods only.

With the above and other objects in view, as will hereinafter appear, the invention comprises the devices, combinations, and arrangement of parts hereinafter set forth and illustrated in the accompanying drawing of a preferred embodiment of the invention, from which the several features of the invention and the advantages attained thereby will be readily understood by those skilled in the art.

Referring to the drawing, Fig. 1 is a fragmentary rear perspective view of a portion of a sewing machine embodying the present invention, showing the thread-cutter and the feeding mechanism by which the thread-cutter is actuated.

Fig. 2 is a top plan view of the usual feed-bar and feed-dog with the boss on the feed-bar in section showing the mounting of the movable cutter-blade.

Fig. 3 is an elevational view of the stationary ledger blade, illustrating the way in which it is fastened to the machine-bed.

Fig. 4 is a left end view of the parts represented in Fig. 3 with the feed-bar and cloth-plate in section.

The present invention, as illustrated in the drawing, is embodied in a sewing machine having a frame including a bed 1 from one end of which rises a bracket-arm 2 terminating in a head 3 overhanging the bed. Journaled in the head 3 is the usual reciprocatory needle-bar 4 carrying at its lower end a threaded needle 5, and a presser-bar 6 sustaining a presser-foot 7. Located beneath the level of the usual work-support or cloth-plate 8, shown in dotted lines in Fig. 1, is a suitable thread-carrying looper 9 which cooperates with the needle 5 in the production of two-thread chain-stitches.

The articles to be stitched are adapted to be advanced past the stitching mechanism by means of a so-called "fcur-motion" feeding mechanism. The actuating connections for the feeding mech-

anism in the machine illustrated are located beneath the level of the cloth-plate 8 and are driven by a rotary main-shaft 10 journaled in the bed 1. The feeding mechanism comprises a feed-dog 11 secured for limited vertical adjustment upon one end of a feed-bar 12, the feed-dog projecting through feed-slots 13 in a throat-plate 14 fastened upon the cloth-plate 8. At its rear end the feed-dog 11 is formed with an offset 15 which increases the width of the feeding surface of the feed-dog, the off-set on the feed-dog cooperating with a relatively vertically yieldable insert 16 on the presser-foot 7, thereby to more effectively chain off between the articles stitched.

10 The feed-bar 12 at its other end is pivotally connected to the bifurcated upper end of a rocking frame 17 journaled upon pintles 18; only one of which is shown, threaded into horizontal lugs 19 integral with the bed 1. Frictionally clamped by means of screws 20 upon the extended hub of the rocking frame 17 is the lower split end of an upstanding rock-lever 21 longitudinally slotted, as at 22, to adjustably receive one end of an actuating pitman 23 embracing at its other end an eccentric 24 secured to the main-shaft 10. Through the connections just described the feed-dog 11 receives its advance-and-return movements, the effective length of these movements being controlled by the position of the end of the pitman 23 in the slot 22 relative to the axis of oscillation of the rock-lever 21.

Rising-and-falling movements of the feed-dog 11 are derived from an eccentric 25 on the main-shaft 10 through the medium of the relatively short vertically disposed pitman 26 pivotally connected at its upper end to the bifurcated end of the feed-bar 12.

The thread-cutter now to be described in detail comprises a stationary ledger-blade 27 and a movable blade 28. As clearly shown in Figs. 3 and 4, the stationary blade 27 at its lower end is preferably formed with a right-angle ear 29 apertured to receive the fastening screws 30 threaded into an upstanding boss 31 integral with the bed 1. Adjacent the upper end the stationary blade 27 is formed with a V-shaped thread-receiving notch 32, the lower edge 33 of which is preferably substantially horizontal and disposed a little beneath the level of the cloth-plate 8, while the upper member 34 is preferably inclined slightly upwardly and is sharpened to provide one cutting edge 34'. Cooperating with this edge 34' is the sharpened edge 35 of the movable blade 28. The movable blade, as shown in Fig. 2, is supported by two horizontal pins 36

journalled for endwise movement in apertures formed in a boss 37 integral with, or otherwise secured to, the feed-bar 12, and is yieldingly biased into contact with the sharpened edge 34' of the stationary blade 27 by a coil-spring 38 disposed in an aperture formed in the boss 37.

In order that the two blades will remain in cutting relation when they are separated to their fullest extent, the movable blade 28 is formed at one end of its cutting edge 35 with a guide or pilot 39. To minimize re-sharpening of the two blades the upper member 34 is bent slightly to the left into a position out of alignment with the remainder of the stationary blade 27, see Figs. 2 and 4, and as the movable blade partakes of the movement of the feed-bar 12, it cooperates with the cutting edge 34' of the stationary blade in true scissors action. That is to say there is but point contact between the two cutting edges as the movable blade is actuated, the movable blade during its cutting action shifting laterally toward the feed-bar 12 in opposition to the coil-spring 38 under the influence of the bent upper member 34 of the stationary blade 27.

Referring to Fig. 1, it will be seen that the V-shaped thread-receiving notch 32 in the stationary ledger-blade 27 opens in the direction of feed. This is desirable because, during normal sewing, the work passes unimpeded over the stationary blade 27, the upper member 34 thereof functioning as a guard-element to protect the work against contact with the movable cutting blade 28. In other words, the upper member 34 of the stationary blade 27 normally holds the work out of range of the movable blade 28 which is actuated continuously during the operation of the sewing machine. In order for the thread-cutter to become effective to sever the thread-chain between the stitched articles, the operator manually introduces the thread-chain into the V-shaped thread-receiving notch 32 while the machine is in operation. It is desirable to have the thread-cutter designed so that it will not be automatically effective to sever the thread-chain unless the operator introduces the thread-chain into the thread-cutter, for in some articles it is desirable to have thread-chains of various lengths extending from the articles.

From the above description, it will be understood that I have provided a thread-cutter which is specially designed to sever the thread-chain between stitched articles, such as filled bags and the like; which operates directly with the feeding mechanism of the sewing machine; and which, although continuously operating, is effective only when the operator desires it to be.

Having thus set forth the nature of the invention, what I claim herein is:

1. In a sewing machine, a frame including a bed and an overhanging head, stitch-forming devices, feeding mechanism including a feed-bar for advancing fabric past said stitch-forming devices, a stationary cutter-blade having formed therein a thread-receiving notch opening in the direction of feed and having one side thereof sharpened to provide a cutting edge, a movable cutter-blade carried by said feed-bar and cooperating with the cutting edge of said stationary blade, and means for yieldingly maintaining the blades in cutting relation with each other.

2. In a sewing machine, a frame including a bed and an overhanging head, stitch-forming devices, feeding mechanism including a feed-bar for advancing fabric past said stitch-forming devices, a stationary cutter-blade having formed in one

side thereof a thread-receiving notch opening in the direction of feed and having one side thereof sharpened to provide a cutting edge, a movable cutter-blade cooperating with the cutting edge of said stationary blade and supported by at least one pin arranged for endwise movement in said feed-bar, and means for yieldingly maintaining the blades in cutting relation with each other.

3. In a sewing machine, a frame including a bed and an overhanging head, stitch-forming devices, feeding mechanism including a feed-bar for advancing fabric past said stitch-forming devices, a stationary cutter-blade having formed in one side thereof a thread-receiving notch opening in the direction of feed and having one side thereof sharpened to provide a cutting edge, a movable cutter-blade cooperating with the cutting edge of said stationary blade and supported by at least one pin arranged for endwise movement in said feed-bar, and a spring acting between said movable blade and said feed-bar for yieldingly maintaining the blades in cutting relation with each other.

4. In a sewing machine, a frame including a bed and an overhanging head, stitch-forming devices, feeding mechanism including a feed-bar for advancing fabric past said stitch-forming devices, a boss formed upon said feed-bar, a plurality of pins journalled for endwise movement in said boss, a cutter-blade supported by said pins and adapted to partake of the movements of said feed-bar, a stationary cutter-blade cooperating with the cutter-blade carried by said feed-bar, and a spring acting between said boss on the feed-bar and the cutter-blade carried by the feed-bar for yieldingly urging the cutter-blade in shearing relation with said stationary cutter-blade.

5. In a sewing machine, a frame including a work-support and an overhanging head, stitch-forming devices and work-feeding mechanism, a stationary cutter-blade projecting upwardly through said work-support and formed adjacent its upper end with a thread-receiving notch opening in the direction of feed, a movable cutter-blade, and means for actuating said movable cutter-blade during operation of the machine.

6. In a sewing machine, a frame including a work-support and an overhanging head, stitch-forming devices and work-feeding mechanism, a movable cutter-blade located rearwardly of the stitch-forming devices, means for actuating said movable blade, and a stationary blade cooperating with said movable blade to provide a thread-cutter, said stationary blade disposed so that its upper end projects above the level of the work-support to provide a guard element extending in a direction away from the stitch-forming devices to protect the fabric being stitched from contact with said movable blade.

7. In a sewing machine the combination with a frame having a work-support, stitch-forming devices and work-feeding mechanism, of a thread-cutter comprising a movable blade, means for actuating said movable blade, and a stationary blade having a cutting edge cooperating with said movable blade, said stationary blade having its cutting edge bent toward the movable blade and its upper end disposed so that it projects above the level of the work-support to provide a guard element extending rearwardly in the direction of the normal feed of the work through the machine to protect the fabric being stitched from contact with said movable blade.

8. A thread-cutting device for a sewing ma-

chine having a feeding mechanism and a work-support, comprising a stationary cutter-blade formed with a thread-receiving notch opening in the direction of the normal feed of the work through the machine and having a portion thereof adapted to project above the level of the work-support, said portion of the thread-receiving notch above the work-support being sharpened to provide a cutting edge, and a movable cutter-blade adapted to cooperate with the sharpened edge of said stationary blade for severing thread introduced into said thread-receiving notch and between said blades.

9. A thread-cutting device for a sewing machine having a reciprocating needle, work-feed-

ing mechanism and a work-support, comprising a stationary cutter-blade formed with a thread-receiving notch opening in the direction of the normal feed of the work through the machine and having a portion thereof adapted to project above the level of the work-support rearwardly of the needle, said portion of the thread-receiving notch above the work-support being sharpened to provide a cutting edge which is bent to a position out of alignment with the remainder of the stationary blade, and a movable cutter-blade adapted to cooperate with the cutting edge of said stationary blade for severing thread introduced between said blades.

HANS HACKLANDER.
